AUTOMOBILE FLOOR MAT

Alfred S. Bachtel, Akron, Ohio, assignor to Seiberling Rubber Company, Barberton, Ohio, a corporation of Delaware

Application December 16, 1957, Serial No. 48,925

Term of patent 14 years

(Cl. D9—6)

Fig. 1 is a top plan view of an automobile floor mat embodying my new design, with certain details of the criss-cross surface area being only partially shown and it being understood that said details cover the entire criss-cross area shown;

Fig. 2 is an enlarged fragmentary plan view of the lower left-hand corner of the mat shown in Fig. 1, showing more clearly such details of surface configuration;

Figs. 3, 4, 5 and 6 are enlarged fragmentary cross-sectional views taken on the lines 3—3, 4—4, 5—5 and 6—6, respectively, on Fig. 1;

Fig. 7 is an enlarged fragmentary sectional view taken on lines 7—7 of Fig. 1; and

Fig. 8 is an enlarged fragmentary sectional view of the mat taken on the line 8—8, Fig. 1.

I claim:

The ornamental design for an automobile floor mat, substantially as shown and described.
